UNITED STATES PATENT OFFICE.

HENRY C. WALDECKER, OF AUSTIN, MINNESOTA.

SAFETY-LOCK FOR FIRE-ARMS.

SPECIFICATION forming part of Letters Patent No. 338,451, dated March 23, 1886.

Application filed September 24, 1885. Serial No. 178,032. (No model.)

To all whom it may concern:

Be it known that I, HENRY C. WALDECKER, of Austin, Mower county, Minnesota, have invented a new and useful Improvement in Fire-
5 Arms, of which the following is a full, clear, and exact description.

The object of my invention is to provide certain new and useful improvements in fire-arms—such as shotguns, rifles, &c.—for the purpose of preventing the premature discharge of the guns, by keeping the trigger locked until the gun is placed against the shoulder for firing.

The invention consists in the construction, 15 and combination, of parts and details, as will be fully described and set forth hereinafter, and then pointed out in the claims.

Reference is to be had to the accompanying drawings, forming part of this specification, 20 in which similar letters of reference indicate corresponding parts in all the figures.

Figure 1 is a longitudinal sectional elevation of a fire-arm provided with my improvement. Fig. 2 is an inside view of the end plate of the 25 butt. Fig. 3 is an outside view of the same.

The trigger A is pivoted in the usual manner, and is provided with the notch A' in its top edge for receiving a lug, B, projecting downward from the inner end of a rod, C, 30 mounted to slide in a tube, D, extending through the stock E from the butt-end to the trigger. A pin, F, is passed through the tube D and through a longitudinal slot, C', in the rod C to limit the movements of said rod. The 35 heel or butt plate G on the butt-end of the stock E is provided with an elongated opening, H, through which a cushion-plate, J, projects from a plate, K, hinged on jaws K' on the inner surface of the heel-plate G, the stock being provided with a recess or cavity, E', in its 40 butt-end, in which recess the plate K can swing. The end of the rod C is pressed against the inner side of the plate K and presses said plate against the inner surface of the heel-plate G 45 by a spiral-spring, L, surrounding the rod C, connected with one end of the same, the spring having its other end rested against the end of the tube D. A tube, M, projects downward and inward from the upper part of the heel, 50 and contains a sliding tube, N, provided with a check-pin, N', projecting into a longitudinal

slot, M', in the tube M. The tube N is pressed outward by a spiral spring, O, resting against the inner end of the tube M and against a screw, P, in the outer end of the tube N. The 55 tube M has a slot, Q, and the tube N a slot, R. On the plate K a prong, S, is formed, which can be passed through slots Q and R.

The operation is as follows: The inner edge of the trigger A rests against the end of the 60 lug B, and thus the trigger cannot be pulled. When the gun is placed against the shoulder, the cushion-plate J is pushed slightly in the direction of the arrow a', and thereby the rod C is pushed in the same direction, and the lug B is 65 brought over the recess or notch A', thus permitting of pulling the trigger. When the plate J is pushed in the direction of the arrow a', the prong S is passed into the slots Q and R of the tubes M and N, which slots register. 70 When the gun is placed on the ground or floor in an upright position, the trigger is not released, for the tube N is pushed inward as soon as the stock is placed on the floor, and this brings the slots Q and R out of register and 75 prevents the prong S from passing through said slots, the tube N thus serving as a locking device or bolt, the same preventing the plate K from swinging in the direction of the arrow a' and moving the rod C sufficiently to permit 80 the trigger to be operated.

Having thus described my invention, I claim as new and desire to secure by Letters Patent—

1. The combination, with the trigger-locking rod and its operating-plate, of the locking-bolt 85 adjacent to said operating-plate and constructed to engage a part thereof and prevent its movement, substantially as set forth.

2. The combination, with the gun-stock and the trigger, of the locking-rod, its operating 90 plate projecting beyond the face of the butt or heel plate and provided with an arm or projection, and a locking-bolt extending beyond the butt-plate at its heel and constructed to engage said arm or projection and lock the operating-plate, substantially as and for the purpose set forth.

3. The combination, with a gun-stock, of a swinging plate in the butt-end of the same, a rod extending from said plate to the trigger, a 95 prong on the swinging plate, a fixed tube in the stock, and a sliding tube in the fixed tube, both

tubes having slots into which the above-mentioned prong can pass when the slots register, substantially as herein shown and described.

4. The combination, with the gun-stock E, of the plate K, pivoted at the butt-end of the stock, the prong S on the said plate K, the rod C, extending from the plate K to the trigger, the fixed tube M in the stock and having the slot Q, the sliding tube N in the tube M and having the slot R, and of a spring for pressing the tube N outward, substantially as herein shown and described.

5. The combination, with the gun-stock E, of

the plate K, pivoted on the butt or heel plate of the stock and having a cushion-plate projecting through an opening in the heel-plate, a rod extending from the plate K to the trigger, the tube M in the stock, the sliding tube N in the tube M, the spring O, for pressing the tube N outward, and the prong S on the plate K, substantially as herein shown and described.

HENRY C. WALDECKER.
